DISPLAY SUPPORT FOR CONTAINERS

Hall Hinkle, Pickens, S. C.

Application March 22, 1950, Serial No. 151,065

1 Claim. (Cl. 248—122)

1

This invention relates to a display stand or rack and more especially to a rack for supporting a plurality of cylindrically-shaped containers such as nail kegs and the like.

It is the object of this invention to provide a stand or rack for supporting a plurality of circularly arranged cylindrical containers, such as nail kegs and the like, in spaced relation to each other and the axes of the containers extending at an angle relative to the vertical to thereby render the contents of the containers easily accessible to an operator.

It is another object of this invention to provide a stand or rack for supporting a plurality of cylindrical containers, such as nail kegs and the like, and comprising a central support member or post having a plurality of radially extending arms thereon for supporting a plurality of containers arranged in spaced relation to each other around the central support member and each of said arms having pivoted support means thereon to permit the container supported thereby to be tilted downwardly at its outer end to permit access to the contents thereof.

It is still another object of this invention to provide a stand or rack having at least two vertically spaced trunnions thereon and each of the trunnions being provided with a plurality of radially extending projections or vanes. A bifurcated arm is secured to and extends radially from each vane and each of the bifurcated arms is provided with two spaced semi-circular members depending therefrom and adapted to support a cylindrical container such as a nail keg. The outermost of said semi-circular members is pivotally secured to the bifurcated arm and has two quarter-circular members secured thereto and extending upwardly therefrom and which are adapted to fit over the top of the keg or the like to clampingly hold the same against the outermost of the semi-circular members and to permit the container to be tilted downwardly at its outer end as desired.

Some of the objects of the invention having been stated other objects will appear as the description proceeds, when taken in connection with the accompanying drawings, in which—

Figure 1 is a top plan view of the display stand, showing a single keg in dotted lines;

Figure 2 is a fragmentary elevation looking substantially along the line 2—2 in Figure 1;

Figure 3 is a vertical sectional view taken along the line 3—3 in Figure 1;

Figure 4 is a vertical sectional view taken substantially along the line 4—4 in Figure 3;

2

Figure 5 is a vertical sectional view taken substantially along the line 5—5 in Figure 3.

Referring more specifically to the drawings, the stand or rack comprises a base member 10 secured to a suitable floor 11 or the like as by bolts 12. The base member 10 has a bore 13 therein in which is suitably secured an uprising central support member or post 15. The uprising member 15 is shown as a pipe, for purposes of illustration, but may be of any desired construction. A pair of spaced trunnions 16 and 17 are rotatably mounted on the member 15 and are held in the desired horizontal position on the member 15 by any suitable means such as collars 20 and 21 secured to the member 15 as by rivets 22 and 23, respectively, said bolts 22 and 23 also penetrating the uprising member 15.

Each of the trunnions 16 and 17 is provided with a plurality of radially extending vanes 25. Since the lower trunnion 16 and the upper trunnion 17 are identical and the supporting arms secured to each vane 25 are identical, the same reference characters will apply to the supporting arms associated with both the upper trunnion 17 and the lower trunnion 16.

A supporting arm broadly designated at 26 is secured to each of the vanes 25 and each supporting arm 26 is bifurcated at its end remote from the member 15 and may be made from a single piece of material, if desired, but is shown as being made of two pieces 27 and 28 of a suitable material, such as channel iron. The channel iron members 27 and 28 are secured at one of their ends to the vane 25 as by bolts 30. The arms 27 and 28 extend outwardly from the member 15 and are bent at right angles in opposite directions from each other, as at 32, and are then again bent at right angles, as at 33, and extend parallel to each other forming arms 35 and 36 spaced apart from each other a sufficient distance to permit cylindrical containers, such as a keg of nails to be inserted therebetween.

A reinforcing plate 37 is secured between the arms 27 and 28 adjacent the point of bend 32, as by bolts 38. The reinforcing plate extends downwardly from the arms 27 and 28 and a brace 41 is secured to the lower portion of the plate 37 as by bolts 42. This brace 41 extends inwardly toward the uprising member 15 and is secured at its inner end to the vane 25 as by bolts 44.

A first semi-circular support member 46 is secured at opposed ends thereof to the arms 35 and 36 adjacent the angle 33 as by bolts 47 and 48, respectively (Figure 5). A second or outermost semi-circular support member 50 is pivot-

ally secured to the arms 35 and 36 as by bolts 51 and 52, respectively (Figure 2). It will be observed in Figures 2 and 3 that the ends of the second semi-circular support member 50 extend upwardly above the uppermost edges of the arms 35 and 36 and have hingedly secured thereto, as at 53, quarter-circular members 55 and 56. The members 55 and 56 have upturned flanges 57 and 58 at their free ends, the flanges 57 and 58 being provided with suitable bores for the reception of a bolt 60 for securing the quarter-circular members 55 and 56 in position, so as to clampingly secure a cylindrical container such as a nail keg K shown in dotted lines in Figure 1.

Referring to Figure 3, it will be observed that the first semi-circular support member 46 extends downwardly at a slight angle from the arms 35 and 36 and is held in this position by the bolts 47 and 48. The second support member 50 also extends downwardly at an angle from the arms 35 and 36 but this last-named member 50 is free to pivot on the bolts 51 and 52.

It will thus be observed that a suitable container such as the keg of nails K may be inserted in the stand so that the lowermost portion of the keg K will rest at one end on the first semi-circular support member 46 and the lower surface of the keg K adjacent its other end will rest on the second semi-circular support member 50.

The angularity of the support members 46 and 50 will cause the right-hand end of the keg K, in Figure 2, to be disposed at a slightly higher elevation than the left-hand end and this right-hand end in Figure 1 may be opened to permit access to the contents of the keg K and the angular disposition of the keg K will prevent the contents from spilling therefrom.

If it is desired to tilt the keg to facilitate removing the contents therefrom, the keg K may be pulled downwardly at its right-hand or outer end in Figure 1 causing the support member 50 to pivot on the bolts 51 and 52 and moving the other end of the keg K out of engagement with the support member 46.

When the keg K is in position on the support members 46 and 50 the quarter-circular members 55 and 56 may be fitted over the top of the keg and the bolt 60 may be tightened in the flanges 57 and 58 to hold the keg K securely in position.

It will be observed that the trunnions 16 and 17 may be rotated on the uprising member 15 so that access may be had to any one of the kegs K disposed in the display stand.

It is thus seen that I have provided a rack in

which a plurality of kegs may be removably mounted and said rack being provided with means for holding a plurality of kegs spaced in a circle around a central point and also being provided with means to permit the easy insertion and removal of said kegs and to permit the same to be tilted to facilitate the removal of the contents therefrom.

In the drawings and specification there has been set forth a preferred embodiment of the invention and although specific terms are employed, they are used in a generic and descriptive sense only and not for purposes of limitation, the scope of the invention being defined in the claim.

I claim:

A rack for supporting a container comprising a support, a pair of outwardly projecting arms secured at one of their ends to opposed sides of said support, said outwardly projecting arms being bent at right angles in opposite directions from each other and then being bent outwardly in parallel relation to each other to form spaced parallel support arms, a first semi-circular member secured to and extending between the spaced parallel support arms upon which one end of the container is adapted to be placed; a second semi-circular member pivotally secured to and extending between the spaced parallel portions of each of the outwardly extending arms and adapted to support a portion of the container whose end is supported by the first semi-circular member, the first and second semi-circular members being arranged with respect to each other so the axis of the container will extend outwardly and upwardly at an angle relative to the horizontal, and means for clampingly securing the container against the second semi-circular support member whereby the second semi-circular support member may be partially rotated for tilting the associated container to assist in removing the contents therefrom.

HALL HINKLE.
